UNITED STATES PATENT OFFICE

150,644

DESIGN FOR A MIRROR

Peter Muller-Munk, Pittsburgh, Pa., assignor to Pro-phy-lac-tic Brush Company, Northampton,
Mass., a corporation of Delaware

Application August 9, 1947, Serial No. 140,796

Term of patent 7 years

(Cl. D86—10)

To all whom it may concern:

Be it known that I, Peter Muller-Munk, a citizen of the United States of America and a resident of Pittsburgh, county of Allegheny, Commonwealth of Pennsylvania, have invented a new, original, and ornamental Design for a Mirror, of which the following is a specification, reference being had to the accompanying drawing forming part thereof.

In the drawing:

Fig. 1 is a front elevation of a mirror showing my new design.

Fig. 2 is a side elevation thereof.

The head of the mirror has the same appearance on both sides. The mirror frame and handle are made of translucent material.

I claim:

The ornamental design for a mirror, substantially as shown and described.

PETER MULLER-MUNK.
